UNITED STATES PATENT OFFICE.

ALBERT ECKSTEIN, OF NEW YORK, N. Y.

DESIGN FOR A HOOK FOR GARMENT-FASTENERS.

SPECIFICATION forming part of Design No. 28,535, dated May 3, 1898.

Application filed March 22, 1898. Serial No. 674,833. Term of patent 3½ years.

To all whom it may concern:

Be it known that I, ALBERT ECKSTEIN, a citizen of the United States, residing at New York, (borough of Manhattan,) State of New York, 5 have invented and produced a new and original Design for Hooks for Garment-Fasteners, of which the following is a specification, reference being had to the accompanying drawings, forming part thereof.

10 Figure 1 is a front perspective view of a hook for garment-fasteners, showing my new design; and Fig. 2 is a rear perspective view of the same.

15 As shown in the drawings, the leading or material features of my design consist of the base-plate A, having a convex edge *a* located

between the sides of the V-shaped and backwardly-bent tongue B, and an opening C, around which the plate A is formed with V-shaped projections *d* and notches *d'*, so that a 20 star appearance is imparted to said opening.

What I claim is—

The design for the hook of a garment-fastener, as shown and described.

In testimony that I claim the foregoing as 25 my invention I have signed my name in presence of two subscribing witnesses.

ALBERT ECKSTEIN.

Witnesses:

GEO. L. WHEELOCK,
GEO. W. JAEKEL.
